LOCKING SLIDER FOR SLIDE FASTENERS

Frederick Ulrich, Bayonne, N. J., assignor to
Commar Products Corporation, Bayonne, N. J.,
a corporation of New Jersey

Application August 1, 1940, Serial No. 349,273

3 Claims. (Cl. 24—205.5)

This invention relates to slide fasteners, and more particularly to locking sliders therefor.

The primary object of my invention is to generally improve locking sliders for slide fasteners. A more particular object is to provide a locking slider having one or more locking projections, each of which is strong, sturdy, and capable of withstanding rough handling and abuse. Another object is to provide a locking projection so shaped that when the tapes are pulled apart the elements are moved more strongly thereagainst, and against the strongest part of the locking projection. Still another object is to provide a locking slider which may be made at substantially no extra cost compared to a non-locking slider and with only a slight negligible change in the die or tool for making the slider.

To the accomplishment of the foregoing, and such other objects as may hereinafter appear, my invention consists in the locking slider elements and their relation one to the other as hereinafter are more particularly described in the specification and sought to be defined in the claims. The specification is accompanied by a drawing, in which:

Fig. 1 is a front elevation of a slider embodying features of my invention;

Fig. 2 is a side elevation of the same removed from the fastener;

Fig. 3 is an inside view of the front wall of the slider;

Fig. 4 is an inside view of the back wall of the slider;

Fig. 5 is a fragmentary section taken in the plane of the line 5—5 of Fig. 4;

Fig. 6 is a fragmentary section taken in the plane of the line 6—6 of Fig. 5;

Fig. 7 is a perspective view of the upper corner of one-half of the slider;

Fig. 8 is a schematic section taken in elevation through a die for forming the slider;

Fig. 9 is a similar view showing the parts in closed relation; and

Fig. 10 is a perspective view of a fragment of the die.

Referring to the drawing, and more particularly to Figs. 1 and 2, the slider generally designated 12 cooperates with a slide fastener which may be of conventional character, the latter comprising tapes 14 having beaded or corded edges 16 on which are clamped a series of interlockable fastener elements 18. Movement of the slider in upward direction causes the elements to interlock and movement of the slider in downward direction disengages the elements.

The slider 12 comprises a front wall 20 and a rear wall 22 joined at a neck 24. In the present case the slider is formed of heavy gauge sheet metal and the walls are indented toward one another at the neck and are there welded to secure the same together. The front wall 20 is preferably provided with a ball or lug 26 which carries a handle or so-called "pull" 28. The side edges of the slider are flanged as is indicated at 30 and 32. These flanged edges may, if desired, be coined to a thinner section than the main body of the slider as is indicated at 34 in Fig. 9. The slider as so far described is substantially the same as that described in my Patent 2,078,745 issued April 27, 1937, and entitled "Slider for slide fasteners and method for making the same."

However the aforesaid slider is here improved by the provision of locking means. One or more locking projections are provided, preferably at the upper inside corners of the slider. In the specific example illustrated in the drawing there are two such projections, marked 40 and 42.

The slider has four upper corners and a locking projection may be provided at any one of the same. It is thus possible to use a single projection, two projections, three projections, or four projections. When two projections are used they may both be formed on the front wall, or both on the back wall of the slider, but I prefer to locate them directly opposite one another, that is, with one on the front wall and the other on the back wall of the slider. Such an arrangement is here illustrated, as is best shown at 40, 42, in Fig. 2.

Referring to Fig. 1, it will be seen that any attempt to open the slider by separating or pulling the tapes 14 apart simply serves to wedge the outer or jaw ends of the fastener elements 18 against the projections, as is indicated by the relation of the elements 44 and 50 to the projection 40 in Fig. 1. This prevents downward movement of the slider, and so locks the fastener against opening.

Fig. 4 shows the back wall of the slider, looking from the inside, and this figure together with Fig. 7 clearly shows how, in accordance with my invention, the outer end of the locking projection 42 is joined integrally with the adjacent flange 32, while the outer side of the locking projection is joined integrally with the adjacent wall 22. Thus the projection 42 is supported and strengthened by its integral connection with two mutually perpendicular walls of the slider. The same applies to the projection 40 on the front

wall, it being integrally joined to flange 38 and wall 28, as is shown in Fig. 3. Moreover, it will be observed from the drawing that the projection diverges to a relatively broad base where it joins the wall and the flange. This feature will be clear from consideration, not only of Fig. 7, but also Figs. 5 and 6. Thus the projection is strongest at its base and outer end. This is an advantageous arrangement because the projections are put under load only when the tapes have been pulled apart in an effort to "tear" the fastener open, and this moves the fastener elements outwardly until they engage the locking projections at their strongest point.

Another advantage of the present construction is the ease of manufacturing the same. Referring to Figs. 8 and 9 it may be explained that the slider is formed between dies 52 and 54 in a manner schematically shown in Figs. 8 and 9. A full thickness blank 56 is disposed between dies 52 and 54 and is compressed by the dies to form the flanges 34. To form the desired locking projection it is merely necessary to notch a corner of the die as is indicated at 58 in Figs. 8 and 10. This is readily done as, for example, by grinding. When such a notched die is employed, the metal which is being compressed or coined flows into the recess 58, thus readily and automatically creating the desired locking projection without necessitating any extra manufacturing operations.

The working or coining of the metal tends to harden the same and this constitutes an additional reason why the locking projections of my invention are capable of withstanding abuse and long wear.

It is believed that the construction and operation, as well as the method of manufacturing my improved locking slider will be apparent from the foregoing detailed description thereof. It will also be apparent that while I have shown and described my invention in a preferred form, changes and modifications may be made in the structure disclosed without departing from the spirit of the invention as sought to be defined in the following claims.

I claim:

1. A locking slider for a slide fastener, said slider comprising front and back walls connected by a neck portion, flanges formed integrally with said walls, and one or more solid locking projections formed integrally with said walls and flanges, the outer end of said projection being joined integrally with the adjacent flange and its outer side being joined integrally with the adjacent wall, whereby said projection is supported and strengthened by its integral connection with two relatively transverse walls of the slider, said projection sloping from flange to wall to permit passage of the slide fastener during the normal operation of said slide fastener.

2. A locking slider for a slide fastener, said slider comprising front and back walls connected by a neck portion, flanges formed integrally with said walls, and one or more solid locking projections formed integrally with said walls and flanges, each said projection being located at an upper corner of the slider, its outer end being joined integrally with the adjacent flange and its outer side being joined integrally with the adjacent wall, whereby said projection is supported and strengthened by its integral connection with two mutually perpendicular walls of the slider, said projection being so located as to permit passage of the slide fastener during the normal operation of said slide fastener.

3. A locking slider for a slide fastener, said slider comprising front and back walls connected by a neck portion, flanges formed integrally with said walls, and one or more solid locking projections formed integrally with said walls and flanges, each said projection being located at an upper corner of the slider, its outer end being joined integrally with the adjacent flange and its outer side being joined integrally with the adjacent wall, said projection diverging to a relatively broad base where it joins the wall, and diverging to a relatively broad end where it joins the flange, said projection sloping from flange to wall to permit passage of the slide fastener during the normal operation of said slide fastener.

FREDERICK ULRICH.
